UNITED STATES PATENT OFFICE

GRAFTON E. LUCE, OF CHICAGO, ILLINOIS, ASSIGNOR TO LANCASTER IRON WORKS, INC., OF LANCASTER, PENNSYLVANIA, A CORPORATION OF PENNSYLVANIA

BRICK-HANDLING APPARATUS

Application filed November 3, 1927. Serial No. 230,704.

This invention relates to brick handling apparatus to be used for handling bricks in the kilns after they have been burned, or taking a unit of bricks from the kilns for loading on barges or cars.

The principal of this invention is to provide a dumping fork of this character adapted to load bricks either in closely packed or loose piles, without any undue breakage. In loading brick for railroad shipment, it has been customary heretofore to carry a load of bricks over the top of a container carried upon a flat bottom gondola car and from that position drop the bricks into the container in a loose pile. The containers for this use are of a standard pattern commonly known as "railroad containers" and are of a depth such that the dumping mechanism of dump forks now in common use can not be reached for operation if the fork is positioned within the container. By means of this invention, the dumping fork may be lowered into the container to within a few inches of the bottom of the car or platform upon which the bricks are to be released. Thereupon a simple release arrangement drops the fork and then by raising the crane, the bricks are rolled off the fork rather than dropped. The crane in its upward movement raises the back end of the fork, leaving the front end lower until finally the whole mechanism assumes a vertical position as it is drawn from the container. To reposition the fork, it is only necessary to lower it to the ground so that it will be brought to horizontal position and locked ready for the next load.

The full nature of the invention will be understood from the accompanying drawings and the following description and claims:

In the drawings, Figure 1 is a side elevation of the fork with the upper portion thereof shown in central vertical cross section, with a stack of bricks carried thereby shown in dotted lines. Fig. 2 illustrates the fork lowered with a load of bricks into a container. Fig. 3 illustrates the fork after having dumped the bricks in the container and being removed therefrom. Fig. 4 is a rear elevation showing the two middle supporting fingers taken on the line 4-4 of Fig. 1. Fig.

5 is a plan view of the locking mechanism. Fig. 6 is a section taken on the line 6-6 of Fig. 1. Fig. 7 is a section taken on the line 7-7 of Fig. 1. Fig. 8 is the same as the upper portion of Fig. 1 showing a modified form. Fig. 9 is a plan view looking down the turning key and ratchet mechanism shown in Fig. 8.

In the drawings there is shown a brick handling or dumping fork which is raised and lowered in the usual manner by a crane connected thru the hooks 10. Suspended from said hooks there is a supporting ring 11 upon which the turn table 12 is rotatably mounted by the ball bearings 13. Rigidly secured to the turn table 12 there is an overhead support 14 having a bracing beam 15 from which are suspended the vertical bars 16. Said bars support the cross beam 17 which is in the form of an inverted channel bar.

The aforementioned structure comprises the frame of the dumping fork which is rotably supported by the turn table 12 so that the fork may be readily swiveled into any desired position for dumping. The said frame and turntable constitute a support for brick supporting fingers hereinafter described.

Pivottally supported by the cross beam 17 upon the finger shaft 18 there are a plurality of brick supporting fingers 19 which extend horizontally or at right angles to the bars 16. As there are a plurality of said fingers they are adapted to support and carry a stack of bricks 20, indicated in dotted lines. However, for dumping the bricks, said fingers are adapted to drop down in the vertical position shown in Fig. 3, swiveling about the shaft 18. For guiding and limiting the extent of their movement, there is provided a stop shaft 21 which moves in the arcuate slot 22, shown in dotted lines, whereby the fingers will be prevented from swinging back of their vertical position when dumping, as well as be forced beyond their horizontal position when resetting.

Mounted in a suitable bracket 23 supported upon the cross bar 17, there is a gear shaft 24 to which is keyed a bevel gear 25. On

each side of said bevel gear there are keyed the spur gears 26 adapted to engage and mesh with the corresponding segmental gears 27 formed upon an arcuate portion of the rear of each finger. There is provided 5 a spur gear 26 for each finger so that upon movement of the fingers 19 about the finger shaft 18, the spur gears 26 are rotated, which in turn rotates the bevel gear 25. Furthermore, the shaft 24 maintains the fingers 19 10 in alignment thruout their movement thru the medium of the spur gears 26 and their respective segmental gears 27.

Meshing with the bevel gear 25 there is 15 a bevel pinion 28 which is keyed to the lock shaft 29 extending vertically upwardly between the bars 16 to the overhead support 14. At the upper end of said shaft 29, there is 20 a gear 30 meshing with the idler gear 31 which in turn meshes with the gear 32 slidably keyed to the holding shaft 33 and having an external bearing in said overhead support 14. Mounted immediately above the bearing on said support and surrounding the shaft 33, there is an annular locking cylinder 34 provided with keyways indicated 25 at 35 in which the locking collar 36 is adapted to slide in and out of locking engagement with the keys 35. Said collar is keyed upon the shaft 33 which is provided with the notch 37 for receiving the pawl 38 pivotally supported by the bracket 39 and normally maintained in engagement with the notch 37 by the spring 40. Pivoted to the under surface 30 of the overhead support 14 there is a locking lever 41 which extends thru the guide member 42 in position to engage the lower end of the lock shaft 33 for moving it into upper locked position.

40 In operation the dumping fork is applied to a stack of bricks in the formation left by the setter wherein the lower course of bricks are sufficiently spaced apart to permit the entrance therebetween of the fingers 45 19, whereby said fingers may thus be positioned under the next upper course. The fingers are held in their horizontal position for supporting the upper courses of bricks by reason of the gears 26 meshing with the 50 segmental gears 27 on the fingers, and be held by the bevel gear 25, bevel pinion 28, shaft 29, gears 31 and 32, shaft 33 and locking collar 36, so that there can be no movement thereof. In other words, when the collar 36 is locked in position by the locking keys 39 against rotation, by reason of its operative connection with the segmental gears on the fingers 19, they are held against rotation thru the shaft 18.

60 The load of bricks is elevated by the crane and lowered into a railroad container 141 so that the fingers rest on or near the bottom thereof. The operator then inserts a pipe 142 into the container so that it passes over the upper end of the shaft 33 and engages

the pawl 38 for forcing it out of engagement with the notch in the shaft, and then engages and forces the locking collar 36 downwardly out of engagement with the locking keys 35. This unlocks the entire mechanism 70 since the collar 36 is free to rotate. This in turn permits rotation of the shaft 33 with the gears associated therewith, whereupon the gears 26 are freely permitted to rotate, thus releasing the fingers 19 so that they are no longer locked in horizontal position. Upon raising the fork by the crane as shown in Fig. 3, the rear ends of the forks are elevated while their front ends, being supported by the bottom of the container or the bricks upon which they rest, are caused to slide rearwardly until the forks are brought to a vertical position limited by the stop shaft 21. This permits the bricks to slide forwardly off the forks. After the dumping action, the fork is then lowered by the crane until the fingers engage a supporting surface, such as the ground, whereupon the continued lowering of the frame causes them to be brought back to horizontal position. Upon this position being reached, the operator moves the lever 41 upwardly from the position shown by dotted lines, thus raising the shaft 33 to which the collar 36 is secured and causing said collar to be reengaged by the locking keys 35 and the pawl 38 to enter the slot 37 by means of the spring 40. Thereupon, the setter is again locked in position to receive the next load of bricks.

65 In the modified form shown in Figs. 8 and 9, the gear 32 is keyed to a pin 133 having a ratchet wheel 134 secured thereto. Pivoted on the table 12 there are pawls 135 adapted to engage with the teeth of the ratchet and prevent rotation thereof in such direction as to release the dumping fingers. Said pawls are normally held in engaging position by the compression springs 136 mounted on the table 12. Said pawls are provided with inwardly-extending portions 137 having a corner normally in engagement with the pin 133.

70 For releasing the ratchet so that the gears 30 to 32, inclusive, may be released for dropping the dumping fingers, there is a tubular wrench 139 having a handle 140. Said wrench is provided with cut-away portions at its lower end adapted to straddle the pin-engaging corner of the ratchet portion 137 when mounted over the upper end of the pin 133. By rotating the handle 140 counterclockwise, the lower end of the wrench 139 at the cut-away portion engages the curved surface of the portion 137 of the ratchet and forces the ratchet out of engagement with the ratchet wheel 134. This releases the gears 30 to 32, inclusive, for permitting the dumping fingers to drop. When the dumping fingers are forced upwardly and to horizontal position, the ratchet 134 is caused to rotate in the direction indicated by the arrow, and the 75 80 85 90 95 100 105 110 115 120 125 130 wrench being removed, the pawl drops into engaging position so that it is held from rotation in the opposite direction, thus sustaining the dumping fingers in position.

5. The invention claimed is:

1. A brick handling fork comprising a support having a downwardly extending portion, a plurality of brick supporting fingers pivotally mounted on the lower end of said

10 downwardly extending portion, a shaft extending from the lower end of said downwardly extending portion to the upper end thereof, a gear connection between the lower end of said shaft and said fingers, and means

15 positioned in the upper portion of said support for locking said shaft against rotation for maintaining said fingers in supporting position and releasing said shaft so as to permit the free rotation thereof, whereby said 20 fingers may freely swing about their pivotal mounting to dumping position.

2. A brick handling fork comprising a support having a downwardly extending portion, a plurality of brick supporting fingers 25 pivoted to the lower end of said downwardly extending portion, a rotatable shaft, extending vertically upward from said fingers means for operatively connecting said shaft and said fingers for preventing the 30 movement of said fingers about their pivotal mounting when said shaft is non-rotative, and a member for locking said shaft against rotation when said member is in one position and releasing said shaft for rotation when 35 said member is in another position.

3. A brick handling fork comprising a support having a downwardly extending portion, a plurality of brick supporting fingers pivoted to the lower end of said downwardly 40 extending portion, a rotatable shaft, extending vertically upward from said fingers means for operatively connecting said shaft and said fingers for preventing the movement of said fingers about their pivotal 45 mounting when said shaft is non-rotative, and a sliding element adapted to lock said shaft against rotation when in one position and release the same for free rotation when moved to another position.

4. A brick handling fork comprising a support having a downwardly extending portion, a plurality of brick supporting fingers pivoted to the lower end of said downwardly extending portion, a rotatable shaft, means 53 for operatively connecting said shaft and said fingers for permitting the movement of said fingers about their pivotal mounting by the rotation of said shaft while locking them in supporting position when non-rotative, a 58 sliding element operatively connected with said shaft for preventing rotation thereof when in one position and permitting its free rotation when in another position, and means for locking said element in said first mentioned position.

5. A brick handling fork comprising an upper supporting frame, a vertical frame depending therefrom, a plurality of fingers pivotally mounted to the lower end of said vertical frame and extending substantially 70 horizontally therefrom for supporting a load of bricks, a locking element slidably mounted in said upper supporting frame, and means for operatively connecting said element with said fingers for normally maintaining said 75 fingers in supporting position and releasing said fingers so as to permit them to move about their pivotal mounting into dumping position when actuated.

6. A brick handling fork comprising an upper supporting frame, a vertical frame depending therefrom, a plurality of brick supporting fingers pivotally mounted on the lower end of said vertical frame, a shaft extending 80 therefrom to said upper supporting frame, a gear connection between said shaft and fingers, a slidably locking element mounted in said upper supporting frame, means for operatively connecting said element with said shaft, and means for 85 locking said element against rotation so as to prevent the movement of said fingers, and releasing said element when moved to another position so as to permit its free rotation and the movement of said fingers to dumping position.

7. A brick handling fork comprising a support having a downwardly extending portion, a plurality of brick supporting fingers pivoted to the lower end of said downwardly extending portion, gear members operatively connected with said fingers and preventing rotation thereof when non-rotative, and means for locking said gear members against 90 rotation and for releasing said gear members for permitting said fingers to drop from said 95 supporting position.

8. A brick handling fork comprising a support having a downwardly extending portion, a plurality of brick supporting fingers pivotally mounted on the lower end of said downwardly extending portion, a substantially horizontal shaft, gear connections between said shaft and said fingers whereby rotation of said fingers is prevented when said shaft is non-rotative, and means for locking said shaft against rotation when said means is in one position and permitting the rotation of said shaft when said means is in another position.

9. A brick handling fork comprising a support having a downwardly extending portion, a plurality of brick-supporting fingers pivotally mounted on the lower end of said downwardly extending portion, a substantially horizontal shaft operatively connected to said fingers to prevent rotation thereof when said shaft is non-rotative, a substantially vertical shaft operatively connected to said horizontal shaft whereby rotation of said horizontal 125 shaft 130

shaft is prevented when said vertical shaft is non-rotative, and means positioned in the upper end of said support for locking said vertical shaft against rotation and for releasing said shaft so as to permit free rotation of said fingers.

10. A brick handling fork for loading railroad containers comprising a support having a downwardly extending portion, brick-supporting fingers pivotally mounted on the lower end of said downwardly extending portion, means for locking said fingers in brick-supporting position, and releasing means for releasing said locking means to permit dumping of the brick, said releasing means being operable from a point exterior of said railroad container when said brick handling fork is positioned within said container, and said locking means and said releasing means being positioned within the vertical projection of the dimensions of said support.

11. An apparatus for loading brick into railroad containers including a dumping fork adapted to support a stack of brick thereon and adapted to be positioned within said container without dumping of brick, means for so positioning the same, and means for actuating said fork for dumping of brick when so positioned.

12. An apparatus for loading brick into railroad containers including a dumping fork adapted to support a stack of brick thereon and adapted to be positioned within said container without dumping of brick, means for so positioning the same, and means for conditioning said fork when so positioned for dumping of brick by the removal of said fork from said container.

13. An apparatus for loading brick into railroad containers including a dumping fork adapted to support a stack of brick thereon and adapted to be positioned within said container, means for so positioning the same, means for actuating said fork for dumping of brick when so positioned, and means for protecting said actuating means against contact with the sides of said container.

14. An apparatus for loading brick into railroad containers including a dumping fork adapted to support a stack of brick thereon and adapted to be positioned within said container without dumping of brick, and means for actuating said fork for dumping of brick when so positioned.

15. An apparatus for loading brick into railroad containers including a dumping fork adapted to support a stack of brick thereon and adapted to be positioned within said container without dumping of brick, and means for conditioning said fork when so positioned for dumping of brick by the removal of said fork from said container.

16. An apparatus for loading brick into railroad containers including a dumping fork adapted to support a stack of brick thereon

and adapted to be positioned within said container, and means for actuating said fork for dumping of brick when so positioned, said actuating means being protected against contact with the sides of said container.

17. An apparatus for loading brick into railroad containers including a frame, a plurality of dumping fingers attached thereto and adapted to support a stack of brick thereon, said frame and said fingers being adapted to be positioned within said container without dumping of brick, and means for actuating said fingers for dumping of brick when so positioned.

18. An apparatus for loading brick into railroad containers including a frame, a plurality of dumping fingers attached thereto and adapted to support a stack of brick thereon, said frame and said fingers being adapted to be positioned within said container without dumping of brick, and means for conditioning said fingers when so positioned for dumping of brick by the removal of said frame and fingers from said container.

19. An apparatus for loading brick into railroad containers including a frame, a plurality of dumping fingers attached thereto and adapted to support a stack of brick, means for locking said fingers to prevent dumping of brick, means for protecting said locking means against contact with the sides of said container, whereby said apparatus may be positioned within said container without dumping of brick, and means for releasing said locking means for dumping of brick when so positioned.

In witness whereof, I have hereunto affixed my signature.

GRAFTON E. LUCE.

DISCLAIMER

1,765,765. *Grafton E. Luce*, Chicago, Ill. BRICK HANDLING APPARATUS. Patent dated June 24, 1930. Disclaimer filed September 8, 1931, by the patentee and the assignee, *Lancaster Iron Works Inc.*

Hereby enters this disclaimer to that part of the claims in said specification which is in the following wording, to wit:

"5. A brick handling fork comprising an upper supporting frame, a vertical frame depending therefrom, a plurality of fingers pivotally mounted to the lower end of said vertical frame and extending substantially horizontally therefrom for supporting a load of bricks, a locking element slidably mounted in said upper supporting frame, and means for operatively connecting said element with said fingers for normally maintaining said fingers in supporting position and releasing said fingers so as to permit them to move about their pivotal mounting into dumping position when actuated.

"10. A brick handling fork for loading railroad containers comprising a support having a downwardly extending portion, brick-supporting fingers pivotally mounted on the lower end of said downwardly extending portion, means for locking said fingers in brick-supporting position, and releasing means for releasing said locking means to permit dumping of the brick, said releasing means being operable from a point exterior of said railroad container when said brick handling fork is positioned within said container, and said locking means and said releasing means being positioned within the vertical projection of the dimensions of said support.

"11. An apparatus for loading brick into railroad containers including a dumping fork adapted to support a stack of brick thereon and adapted to be positioned within said container without dumping of brick, means for so positioning the same, and means for actuating said fork for dumping of brick when so positioned.

"12. An apparatus for loading brick into railroad containers including a dumping fork adapted to support a stack of brick thereon and adapted to be positioned within said container without dumping of brick, means for so positioning the same, and means for conditioning said fork when so positioned for dumping of brick by the removal of said fork from said container.

"13. An apparatus for loading brick into railroad containers including a dumping fork adapted to support a stack of brick thereon and adapted to be positioned within said container, means for so positioning the same, means for actuating said fork for dumping of brick when so positioned, and means for protecting said actuating means against contact with the sides of said container.

"14. An apparatus for loading brick into railroad containers including a dumping fork adapted to support a stack of brick thereon and adapted to be positioned within said container without dumping of brick, and means for actuating said fork for dumping of brick when so positioned.

"15. An apparatus for loading brick into railroad containers including a dumping fork adapted to support a stack of brick thereon and adapted to be positioned within said container without dumping of brick, and means for conditioning said fork when so positioned for dumping of brick by the removal of said fork from said container.

"16. An apparatus for loading brick into railroad containers including a dumping fork adapted to support a stack of brick thereon and adapted to be positioned within said container, and means for actuating said fork for dumping of brick when so positioned, said actuating means being protected against contact with the sides of said container.

"17. An apparatus for loading brick into railroad containers including a frame, a plurality of dumping fingers attached thereto and adapted to support a stack of brick thereon, said frame and said fingers being adapted to be positioned within said container without dumping of brick, and means for actuating said fingers for dumping of brick when so positioned.

"18. An apparatus for loading brick into railroad containers including a frame, a plurality of dumping fingers attached thereto and adapted to support a stack of brick thereon, said frame and said fingers being adapted to be positioned within said container without dumping of brick, and means for conditioning said fingers when so positioned for dumping of brick by the removal of said frame and fingers from said container.

"19. An apparatus for loading brick into railroad containers including a frame, a plurality of dumping fingers attached thereto and adapted to support a stack of brick, means for locking said fingers to prevent dumping of brick, means for protecting said locking means against contact with the sides of said container, whereby said apparatus may be positioned within said container without dumping of brick, and means for releasing said locking means for dumping of brick when so positioned."
